G. C. VOLLMER.
KNIFE SHARPENER.
APPLICATION FILED SEPT. 13, 1920.

1,429,984.

Patented Sept. 26, 1922.

Inventor
Gustav C. Vollmer.

UNITED STATES PATENT OFFICE.

GUSTAV C. VOLLMER, OF ST. LOUIS, MISSOURI.

KNIFE SHARPENER.

Application filed September 13, 1920. Serial No. 409,752.

To all whom it may concern:

Be it known that I, GUSTAV C. VOLLMER, a citizen of the United States, and resident of St. Louis, Missouri, have invented certain 5 new and useful Improvements in Knife Sharpeners, of which the following is a specification.

This invention relates to improvements in a knife sharpener, and has for its object a 10 plurality of adjustable sharpening members clamped on a supporting body and arranged interjacent to each other, forming a V-shaped recess into which the edge of a knife blade is inserted and sharpened by drawing the 15 blade through said recess.

A further object of my invention is to construct a simple device which has a plurality of members arranged interjacent to each other; the inner edges being provided 20 with a roughened sharpening surface against which the cutting edge of the knife is brought in contact and the edge sharpened.

Figure 1, is a perspective view of my complete invention.

Fig. 2, is a side view of the same showing the knife blade in position in the act of being inserted.

Fig. 3, is an end view of the same.

Fig. 4, is a detail perspective view of the base.

Fig. 5, is a horizontal sectional view taken on the line 5—5 of Fig. 3.

In the construction of my invention I 35 provide a base member 5, consisting of a sheet of material suitably bent forming a supporting section 6, and an ear 7, the supporting section being constructed preferably angular in form. Two surfaces of supporting section 6 are provided with a plurality of lugs 8 between which are placed sharpening members 9. The two surfaces are also provided with internally screw-threaded bores 10, into which is inserted a screw 11, by 40 which a clamping plate 12 is held in position and against the sharpening members which are seated between the lugs 8.

Each of the sharpening members 9, is 50 constructed of a strip of steel, preferably octagon in cross-section, one surface of each of the members being serrated forming a cutting edge 13. This edge is constructed preferably in the form of a file and on account of the octagonal shape, the surfaces 55 14 form bevels which when the members are

properly located in position on the supporting member 6 form between adjacent cutting edges a space sufficient to permit the particles of steel removed from the knife blade to pass downwardly and out of the 60 way, so as not to interfere with the blade; and yet cause the device to form a smooth and sharp cutting edge on the knife.

These sharpening members are arranged as shown in the angular body, so that the 65 upper portions cross each other forming a V-shape recess and the members are firmly held in proper adjusted position by the clamping plates 12. By means of these plates and whenever it is found necessary to adjust the sharpening members, each individual member can be raised or lowered by releasing the clamping plate and then held in locked position by tightening said plates.

The essential feature of my invention is 75 to construct a knife sharpening device by providing a plurality of sharpening members arranged in the form of a X and interjacent to each other, and yet providing sufficient space between the cutting edge of 80 each member to permit the removed particles from the blade to pass out un-interrupted.

Having fully described my invention what I claim is:

1. A knife sharpener comprising a tapered base; a plurality of sharpening members supported on said base and arranged interjacent to each other, said sharpening members being octagonal shaped in cross 90 section and means for supporting said sharpening members in their set position, substantially as specified.

2. A knife sharpener comprising a one piece base; the upper portion thereof arranged triangular in form; sharpening members supported on the triangular portion of said base; said sharpening members arranged interjacent to each other, the upper portions forming a V-shaped recess into 100 which the blade to be sharpened is inserted and fastening devices for supporting the sharpening members in rigid position, substantially as specified.

3. A knife sharpener comprising a base 105 formed of a bent sheet of material; the upper portion of said base being tapered in form; a plurality of sharpening members supported on the tapered portion of said base; said sharpening members being elong- 110

gated and in cross section octagonal in form; the upper surface of said sharpening members being serrated and forming a sharpening surface, said sharpening members being interjacent to each other, and by means of the octagonal shape, forming spaces between each pair of adjacent members through which the particles removed from the knife edge are permitted to pass out uninterrupted, substantially as specified.

4. A knife sharpener comprising a base; constructed of a sheet of material suitably bent forming a supporting portion; an ear and a plurality of lugs formed on the supporting portion; sharpening members located between the lugs, each of said sharpening members having a serrated surface and said members being so arranged as to be located interjacent to each other bringing the serrated surfaces in position to be rubbed

against by the knife to be sharpened, substantially as specified.

5. A knife sharpener comprising a plurality of elongated sharpening members octagonal in cross section; a base on which said sharpening members are mounted and arranged to cross each other forming a V-shaped recess at the upper end at which the article to be sharpened is inserted; a fastening means by which the sharpening members are held in position, substantially as specified.

In testimony whereof, I have signed my name to this specification, in presence of two subscribing witnesses.

GUSTAV C. VOLLMER.
